United States Patent Office

Des. 228,418
Patented Sept. 18, 1973

228,418

HOLDER FOR A WRITING INSTRUMENT OR SIMILAR ARTICLE

John E. Locke, Las Vegas, Nev., assignor to Easyrider,
Inc. (also known as Easy Graphic Systems, Inc.), Clinton,
Ohio

Filed Apr. 1, 1971, Ser. No. 130,564

Term of patent 14 years

Int. Cl. D19—06
U.S. Cl. D74—17 B

FIG. 1

FIG. 2

FIG. 3

FIG. 4

FIG. 5

FIG. 6

FIG. 1 is a perspective view of a holder for a writing instrument or similar article showing my new design;

FIG. 2 is a top plan view;

FIG. 3 is a left side view thereof slightly in perspective;

FIG. 4 is a bottom view;

FIG. 5 is a front view thereof as seen from the left of FIG. 3; and

FIG. 6 is a rear view thereof as seen from the right of FIG. 3.

I claim:

The ornamental design for a holder for a writing instrument or similar article, as shown.
